UNITED STATES PATENT OFFICE.

WILLIAM E. AYCOCK, OF MOULTRIE, GEORGIA.

PENCILING-GUIDE.

1,211,038.

Specification of Letters Patent. Patented Jan. 2, 1917.

Application filed May 5, 1916. Serial No. 95,589.

To all whom it may concern:

Be it known that I, WILLIAM E. AYCOCK, a citizen of the United States of America, and a resident of Moultrie, Georgia, have 5 invented a new and useful Improvement in Penciling-Guides, which invention is fully set forth in the following specification.

This invention relates to a penciling guide, and has a special utility for guiding 10 a brush or pencil in painting or penciling the bottoms of grooves in scratch-joint brick-work, particularly the bottoms of grooves in wood surfaces imitating such brick-work.

15 This invention, which in certain respects is an improvement over the construction disclosed in my Patent No. 1,164,449, granted December 14, 1915, has for an object to provide a penciling guide for a paint-brush or 20 pencil of any preferred kind that will insure against paint being dragged by the guide along the side walls of the groove as the guide is moved therein from one place to another.

25 It has for a further object to provide a guide that will enable equally efficient use although there be slight variations in the width of the groove, and that will enable the guide to be resiliently forced into engagement with the corners formed by the 30 base and side walls of the groove.

Other objects are to provide a guide that may be easily and inexpensively constructed and that will be efficient and satisfactory 35 in use.

While the invention is susceptible of embodiment in a variety of mechanical expressions, one of which has been selected for illustration in the accompanying drawing, 40 it is to be expressly understood that such embodiment is not definitive of the invention, reference being had to the appended claims for a definition of the scope thereof.

Figure 1 shows diagrammatically the pencil guide of this invention in operative relation in a groove such as presented by imitative brick-work; Fig. 2 is a plan view of the guide on an enlarged scale; Fig. 3 is an elevation illustrating the guide in 50 working relation with a groove and indicating its manner of use.

Referring in detail to the drawing, where in similar characters of reference indicate corresponding parts, Fig. 1 shows a section 55 of wood grooved longitudinally and transversely to produce the semblance of scratch-

joint brick-work. In order that the protruding rectangular portions 1 shall stand out in relief and closely resemble brick-work the bottoms of the grooves 2 must be 60 given a different color from that employed on the face and sides of the sections 1. It therefore becomes necessary that a guide shall be provided insuring against the brush or pencil contacting with the side walls of 65 the grooves. Furthermore, in moving the guide from place to place along a groove, it is essential that the guide shall not drag or smear the paint on the side walls thereof. To this end the sides of the guide are 70 inclined inwardly and upwardly to provide the clearance, as shown at 3, so that they will be out of contact with the side walls of the groove except at their lower edges. To insure also against the paint being dragged 75 longitudinally of the grooves as the guide is moved, the guide is recessed at the lower portion of each end, as shown at 4. To insure that the brush or pencil shall be guided into the proper position between the side 80 walls, and to provide for the convenient manipulation of the guide, it is provided with flaring ledges 5 and 6, preferably extending throughout the length thereof and 85 of uniform width.

While the guide may be constructed in any suitable or desired way, a preferred manner of construction is as follows: Two similar sections, preferably of a width somewhat greater than twice the depth of the 90 groove with which the guide is to be used, are pressed from sheet metal, and each section is cut away at each corner to provide ears 7-7 and 8-8 at either end and preferably to one side of the longitudinal center 95 line of the section. Each section is then bent along a longitudinal line, preferably in alinement with those edges of the ears near the center line of the section, whereby are formed the upwardly and inwardly inclined side walls 9 and 10 and the upwardly and outwardly inclined ledges 5 and 6, the depth of the space between the walls 9 and 10 being somewhat greater than the depth 100 of the groove. The aforesaid ears are next bent substantially at right-angles to the body portion of each section and the two sections joined by rivets passed through these ears. Thereby is formed a guide having upwardly and inwardly inclined sides 105 110 providing the clearance at 3, and upwardly and outwardly inclined ledges which will

guide the brush or pencil into the space between the side walls 9 and 10 and which will also serve as finger-grips for holding the guide in position. The cut-away portions 5 at the lower corners also provide the recesses 4 at either end, as heretofore described. As these ledges 5 and 6 are of uniform width and extend throughout the length of the guide, the latter may be conveniently held thereby at any portion thereof. By slightly pressing the ledges between the thumb and finger, the lower edges of the guide will be forced into snug engagement with the corners of the groove formed by 15 the bottom and side walls thereof, and as the two sections may give slightly about the axis determined by the rivets, the guide can be accommodated to grooves differing somewhat in width. Furthermore, by forcing 20 the lower edges into engagement with the corners of the grooves, as heretofore described, the guide will resiliently grip the side walls of the groove exterior thereto and remain in position although the hand 25 be withdrawn.

It will be apparent that the inclination given to the side walls of the guide insures against paint being dragged or smeared along the side walls of the groove, while 30 the recessed ends of the guide insure against the paint being dragged along the bottom of the groove, as the guide is moved from place to place.

It will be understood that the guide for 35 use in the transverse grooves 11 is of the same construction as heretofore described but shorter to conform with the length of such grooves.

While the preferred embodiment has 40 been described with considerable detail it is to be expressly understood that the invention is not restricted to such embodiment, other mechanical expressions of the invention readily suggesting themselves to 45 those skilled in the art.

What is claimed is:—

1. A penciling guide having upwardly and inwardly inclined oppositely disposed side walls, and means connecting the same.
2. A penciling guide having upwardly and inwardly inclined oppositely disposed side walls, means connecting the same and upwardly and outwardly inclined ledges extending thereabove.
3. A penciling guide having upwardly and inwardly inclined oppositely disposed side walls, means connecting the same and upwardly and outwardly inclined ledges of uniform width extending thereabove.
4. A penciling guide having upwardly and inwardly inclined oppositely disposed side walls provided with inwardly directed

ears at each end and means connecting opposed ears whereby the side walls are held in spaced relation.

5. A penciling guide having upwardly and inwardly inclined oppositely disposed side walls provided with inwardly directed ears at each end, upwardly and outwardly inclined ledges extending above said side 70 walls, and means connecting opposed ears whereby the side walls are held in spaced relation.

6. A penciling guide comprising similar sections bent along a longitudinal line to 75 provide upwardly and inwardly inclined oppositely disposed side walls and upwardly and outwardly inclined ledges extending thereabove, and means connecting the same.

7. A penciling guide comprising similar sections bent along a longitudinal line to provide upwardly and inwardly inclined oppositely disposed side walls and upwardly and outwardly inclined ledges 85 extending thereabove, and connecting means maintaining said sections in spaced relation while admitting of slight angular movement of said sections about a longitudinal axis.

8. A penciling guide comprising similar sections bent along a longitudinal line to provide upwardly and inwardly inclined oppositely disposed side walls and upwardly and outwardly inclined ledges 95 extending thereabove, and inwardly directed ears extending from each end of said sections and connected to admit of slight angular movement of said sections about a longitudinal axis.

9. A penciling guide comprising similar sheet metal sections bent along a longitudinal line to provide upwardly and inwardly inclined oppositely disposed side walls and upwardly and outwardly inclined ledges 105 extending thereabove, said sections being provided with inwardly directed ears at each end connected to maintain said sections in spaced relation.

10. A penciling guide comprising opposed longitudinal walls which are shaped to transversely approach and then recede from each other, and connecting means maintaining said walls in spaced relation.

11. A penciling guide comprising opposed longitudinal walls which are shaped to transversely approach and then recede from each other, and means maintaining said walls in spaced relation, said means joining said walls at points adjacent the 115 plane of nearest approach of such walls.

In testimony whereof I have signed this specification.

WILLIAM E. AYCOCK.
